UNITED STATES PATENT OFFICE.

IRVIN L. YOUNG, OF CHICAGO, ILLINOIS.

TAG-WIRING MACHINE.

Application filed August 18, 1923. Serial No. 658,058.

To all whom it may concern:

Be it known that I, IRVIN L. YOUNG, a citizen of the United States, residing at Chicago, in the county of Cook and State of Illinois, have invented new and useful Improvements in Tag-Wiring Machines, of which the following is a specification.

This invention relates to tag wiring machines and has for one of its objects the provision of a machine of this character for attaching a tying wire to a tag during its continued and uninterrupted movement through the machine.

Another object is to provide the machine with means for feeding the tags in rapid succession to the wire feeding means.

A further object is to provide the machine with wire twisting means co-operating with the wire feeding means for efficiently attaching the tying wires to the tags.

A still further object is to provide the machine with means for receiving the tags with their attached tying wires from the wire feeding and the wire twisting means and conveying the completed tags to the delivery end of the machine.

These and other objects will more fully appear and the nature of the invention will be more clearly understood from the following specification read in connection with the accompanying drawings and the subject matter of the appended claims.

In the drawings,

Figure 1 is a top view of the machine; Fig. 2 is a side view of the upper portion of the machine showing the same as broken off from its supporting base or stand;

Fig. 3 is a side view of the supporting base or stand for the machine, also shown as broken off therefrom;

Fig. 4 is an end view of the tag feeding magazine;

Fig. 5 is a fragmentary sectional view of the delivery end of the tag feeding magazine showing the means for ejecting the tags therefrom;

Figure 5^a is a section taken on the line 5^a—5^a of Fig. 5.

Fig. 6 is a fragmentary side view on line 6—6 of Fig. 1, partly in section, of the plunger releasing arm for removing the tags as fed from the magazines to the loading spindles;

Fig. 7 is a transverse sectional view on

line 7—7 of Fig. 2, looking in the direction of the arrows, showing certain details of construction of the wiring mechanisms;

Fig. 8 is a vertical sectional view on line 8—8 of Fig. 2 drawn through one of the wire directing members;

Fig. 9 is a vertical sectional view on line 9—9 of Fig. 7 showing the temporary retaining forks for holding the loading spindle, shown in dotted lines, and which carries the tag, in registration with the wire directing member, shown in Fig. 8, for inserting the wire through the opening in the tag, and the opening in a certain movable tension member.

Fig. 10 is a view on line 10—10 of Fig. 2 looking in the direction of the arrows and showing the lower stationary cam and upper rotating cam employed at the feeding end of the machine, and

Fig. 11 is a view on line 11—11 of Fig. 2 looking in the direction of the arrows and showing the lower stationary cam and lower rotating cam also employed at the feeding end of the machine.

Referring to the drawings, 1 indicates the base of the machine having mounted thereon the standards 2 which are four in number and support the machine plate or table 3 at each of the corners thereof. Approximately centrally mounted upon the base 1 is the stationary post 4 which projects through the table 3 and for a distance thereabove. There is mounted upon the base 1 at any suitable point thereon a revolving shaft 5 which also projects through the table 3 and for a distance thereabove, the lower end of the shaft 5 being provided with a bevel gear 6 which meshes with the bevel pinion 7 which is revolved by any power source

through suitable connections, such as fast and loose pulleys 8. Secured to the upper portion of the shaft 5 above the table 3 is a large gear wheel 9 meshing with a second gear wheel 10 rotatably mounted upon the stationary post 4. Secured upon the main driving shaft 5 above the bevel gear 6 is a grooved pulley 11 connected by a belt 12 to a grooved hub pulley 13 of the main grooved pulley 14. The pulley 14 is connected by the belt 15 projecting through openings formed through the table 3, the function of belt 15 to be later described. Secured upon the main driving shaft 5 at a point just beneath

60

65

70

75

80

85

90

95

100

105

the bottom of the table 3 is a sprocket wheel 16 connected by the sprocket chain 17 to another sprocket wheel 18 secured upon the lower end of the shaft 19 having at its upper 5 end the bevel gear 20 meshing with the bevel gear 21 for revolving the horizontal shaft 22, see Fig. 1. The above describes the main power operating mechanisms of the machine.

Supported upon the table 3 by the standards 23 is the tag feeding magazine 24. The latter is medially recessed to receive a longitudinally slidable floor plate 25, and at the sides, the magazine receives two pairs of supports 29, these being rigidly secured to the 10 magazine by screws 29^a or other suitable fastening means. Within the area bounded by the supports 29 is positioned a guide for the supply of tags, comprising laterally-spaced sections, each composed of rearward and forward upstanding members 26 and 27, respectively. The members 27 are relatively shorter than the members 26; and the sections are held in rigid relation by truss bars 27^a. These have outward rods 28 extending 15 slidably into the supports 29, whereby the spacing of the guide sections may be varied in accordance with the width of the tags received. A desired spacing may be fixed by adjusting set screws 30 mounted in the supports 29 to bear on the rods 28. The plate 25 is reciprocated within the magazine by the post 31 connected by the link 32 to the pivotally mounted link 33 which is rocked in one direction by the link 34 connected to the 20 arm 35 having at one end a cam roller 36 and at its other end the post 37 to which one end of the spring 38 is attached, the other end of the spring 38 being attached to the guide block 35^a for guiding the arm 35. 25 Upon the magazine is a stop 39 for limiting the backward movement of the plate 25.

Beyond the tag guide, the supports 29 receive a device which, in conjunction with the plate 25, limits the feed to one tag during each instroke of the plate. The device has a cross bar 39^a for a base, which is secured to the inner pair of supports 29 by bolts 39^b. As shown more clearly in Fig. 5, the cross bar 39^a receives a block 39^c by 30 means of a bolt 39^d this block carrying a depending shoe 39^e to serve as a leveling guide for the tags and as a check against the return of a tag by obstructing the eye-patch or tab at the head thereof. The block 35 also receives a gage 41 which is vertically adjustable through the action of a set screw 41^a in conformity with the thickness of a given tag, whereby to permit but one tag to pass on each instroke of the plate 25. 40 The gage 41 is moved by a collar 41^b carried by the screw 41^a receiving the collar in a slot 41^c, as indicated in Fig. 4, and slides in an undercut face-recess of the block 39^c, as clearly shown in Fig. 1.

65 The plate 25 is horizontally slotted at its

inner end to receive the enlarged end 40^a of a spring-finger 40 extending inwardly and terminating in a slight upward turn just beyond the end of the plate. Figure 5^a shows more clearly that the plate is slotted above 70 the enlargement 40^a to receive a square washer 40^b and a screw 40^c, whereby to firmly secure the finger 40 to the plate. The function of the finger is to enter with its terminal turn or point into the hole in the 75 head of the lowermost tag on the outstroke and in that manner push such tag forward on the instroke.

80 Mounted upon the table 3 are the posts 42 for supporting the lower stationary cam 43 and the upper stationary cam 44, the cam 43 being provided with the guide opening 45 and the cam 44 being also provided with the guide opening 46, clearly shown in Figs. 1, 2, 10 and 11.

85 Secure upon the shaft 5 and adapted to be revolved therewith is the lower movable cam 47 above the stationary cam 43 and being provided with the upstanding cam flange 48. Also secured upon the revolving shaft 5 is the upper movable cam 49 positioned at a distance beneath the stationary cam 44. The lower movable cam 47 is provided with the oppositely disposed substantially triangular 90 guide openings 50, the upper movable cam 49 being also provided with guide openings 51 similar to the guide openings 50 of the cam 47 and in vertical alinement therewith. Operatively mounted within the respective 95 guide openings of the stationary and movable cams are the loading spindles 52 oppositely disposed from each other and supported by the ends of the upper and lower leaf springs 52^a and 52^b, the opposite ends of the leaf springs 52^a being secured to the 100 studs 53 secured to the underside of the upper movable cam 49; the opposite ends of the lower springs 52^b being secured to the studs 54 secured to the upper side of the lower movable cam 47. The spindles 52 are provided with the spool-like members 52^c upon their portions between the movable cam 49 and the stationary cam 44 and being provided at their upper ends projecting slightly 105 above the upper surface of the cam 44 with the pintle or point 52^d, whereby upon the rotation of the cams 47 and 49 the spindles 52 will be moved in accordance with the respective openings in the stationary and movable cams so as to bring the pintles 52^d alternately 110 in a manner to present the pintles 52^d at the discharge end of the magazine for receiving the tags as the same are ejected therefrom and thereafter moving the tags for placing the same upon a portion of the wiring mechanism. It will be obvious that the finger 40 acts to assure registration of the tag opening with the pintles 52^d. Co-operating with the spindles 52 is the spring 115 pressed plunger 55 (see Figs. 6 and 2) of 120

the head 55^a carried upon one end of the swinging arm 55^b having its opposite end formed with a hub 55^c adjustably secured by the set screw 55^d upon the vertically disposed rod 55^e journaled through the guide bracket 55^f secured upon the magazine at its feeding end the rod 55^e projecting below the bracket 55^f and having its lower end secured to the head 55^a of a laterally projecting rod 10 or bar 55^g carrying at its free end the cam roller 55^h for riding upon the upper surface of the cam flange 48 of the cam 47, there being interposed between the bracket 55^f and the head 55^a a spring 55ⁱ for holding 15 the cam roller 55^h in constant engagement with the cam flange 48, whereby when the cam roller 55^h enters a depression 55^k in the surface of the cam flange 48, the arm 55^b will be lowered through the action of the 20 compression spring 55ⁱ so that the plunger 55 will engage the ejected tag at a time when the pindle 52^a of the loading spindle 52 is immediately beneath the ejected tag so as to co-operate therewith for placing the ejected 25 tag upon the pindle 52^a, which pindle 52^a will convey the tag from the magazine to the wiring mechanism to be described. The action assumed by the three elements dealing with the tag, viz., finger 40, plunger 30 55 and pindle 52^a is as follows: The finger 40, at the end of its forward or instroke, extends across the tag opening, but being a light spring readily yields as the plunger 55 descends. As the plunger 55 enters the tag, 35 the finger begins its outstroke, tripping the slight impediment presented by the nose of the plunger. At this time the pindle 52^a has arrived into alinement with the plunger, and the further descent of the plunger head 55^a maintains this alinement, the plunger backing into the cavity of the head against the tension of a spring 55ⁱ while the pindle is received in a transverse slot 55^m cut in the bottom of the plunger head. The tag in the meantime is depressed onto the pindle by the head 55^a. The pindle now departs, 40 emerging from the slot 55^m. Secured upon the upper portion of the gear wheel 10 are the posts 56, which are 45 four in number, for supporting in vertically spaced relation above the gear wheel 10 and the upper stationary cam 44, hereinbefore described, the wire feeding supporting disk or spider 57 provided with the equally spaced holders 58 receiving wire directing tubes 58^b, the holders 58 being provided with the under-cut portions 58^c beneath the collar 58^d secured upon the upper projecting ends of the wire directing tubes 58^b by the set screws 58^e to provide for the ready removal of the wire directing tubes in case of repair. Slidably mounted in the upper portion of the tube 58^b is a second wire directing tube 58^f normally forced upwardly by the 50 compression spring 58^g which is seated in an annular recess in the upper portion of the tube 58^b and bears against the under side of the head 58^h of the tube 58^f. Above the spider or disk 57 and vertically spaced therefrom is the cam member 59 rigidly secured 55 upon the stationary post 4 having a cam face 59^a upon its under side provided with a predetermined located upwardly extending concavity 59^b and engaging the cam face 59^a and the concavity 59^b thereof are the cam rollers 59^c upon the pivotally mounted arms 59^d provided with the forked ends 59^e having the inwardly extending pins 59^f for engaging the under side of the collar 58^d by way of the under-cut recesses 58^c of the holder 58^a for raising at the proper time the wire directing tube 58^b against the tension of the compression spring 58^g when the cam roller 59^c enters the concavity 59^b of the cam 59. Normally, the compression 60 spring 58^g maintains the tube 58^b in depressed or lowered position, whereby to guide the wire through the hole in the tag which has been placed by the pindle 52^a upon the fingers 60 and subsequently held against 65 the lower end of the wire feeding tube 58^b for receiving a half-length of the wire already fed down the tube 58^b by means soon to be described, the tag being held firmly against the tube 58^b by the action of the 70 springs 60^a which has one end attached to the post 56 and its other end attached to one end 60^b of a bell crank arm 60^c pivotally mounted upon the post 56. The fingers 60 are continuously held in upward position 75 until prior to their reaching the tag loading position, whereby the inner end of the plunger rod 60^d which projects through the post 56 and engages the bell crank arm 60^c rides upon the cam 60^e fixed upon the stationary 80 post 4 thus causing the plunger rod 60^d to be forced in outward direction against the bell crank arm 60^c to force the arm 60^c together with the fingers 60 downwardly for receiving 85 the tag from the point of the loading spindle 52, whereby to receive the next succeeding tag in a manner just described. The loading spindle 52 is engaged by the upper and lower forked arms 61 and 61^a for temporarily checking the movement of the loading spindle 52 and for retaining the same with the tag in registration with the wire feeding tube 58^b at which time the fingers 60, which are now below the tag, may rise 90 and transfer the latter from the spindle 52 to the conical point of the tube 58^b. Therefore, the tag will be held in a position so that the wire may be projected through the hole in the tag with precision. The forked arms 61 and 61^a are carried by the posts 56, and are positioned in vertical alinement with the tag holding fingers 60 and the wire feeding tube 58^b, since these parts are mounted 95 on the unitary structure which rotates with the gear base 10. 100

The engagement of the loading spindle 52 with the upper and lower forked arms 61 and 61^a is occasioned by the operation of the cam openings 45 and 51 as affected by the combined rotary movement of the cams 47-49 and of the unitary structure carrying the feeding tubes 58^b and the alined forked arms 61 and 61^a. Thus, the outward tension of the spindles 52 is normally limited by the contour of the cam openings 45, but is released by such contour at the site of the arms 61 and 61^a whereby the latter take the place of such contour and temporarily check and retain the spindles in a position alined with the feeding tubes 58^b, all while the rotary movement goes on.

Suitably supported upon the disk or spider 57 are the supporting cylinders 62, passing through which and the disk or spider 57 and the wire reel supporting plate 62^a are the retaining bolts 62^b for rigidly supporting the wire reel plate 62^a, upon the upper side of which are the wire reels 63, being four in number or any suitable number, and from which the wires pass around the pins 63^a and continue between the intermittent feeding rolls 63^b which feed the wire to the wire delivering tubes 58^b and 58^c, each feed roll 63^b being mounted upon a shaft 63^c rotating in a bracket 63^d secured to the under side of the wire supporting disk 62^a, the inner ends of each of the shafts of the feed rolls 63^b being provided with a gear pinion 64 adapted to mesh at predetermined intervals with the segmental racks 64^a upon the stationary disk or plate 64^b rigidly secured upon the stationary post 4.

The gear 10 is revolved through the medium of the gear 9 and revolving therewith around the stationary post 4 are the posts 56 supporting the plate or spider 57, the supports 62 supporting the wire reel supporting plate 62^a and their accessories forming a substantially unitary structure for revolving simultaneously with the gear wheel 10.

During the operation of the machine when a wire directing tube 58^b registers with the pintle 52^c of the tag loading spindle 52 for placing the tag upon the fingers 60, a portion of the wire is projected through the aperture in the tag by a movement of the feed rolls 63^b, the tag 65 being held firmly against the wire directing tube 58^b by the upward pressure of the fingers 60 while the pinions 64 engage another rack segment 64^a, whereby the wire will be further fed through the tag as the tag holding means continues in its travel. The wire, before entering the directing tube 58^b, passes through the aperture in a stationary member 65^a secured upon the bottom bracket 63^d and also through a similarly apertured member 65^b which is pivotally mounted

upon the member 65^a by the bolt 65^c, the member 65^b being held normally in registration with the member 65^a by the torsion spring 65^d, which at the same time presses the knife members 65^b and 65^a together. 70

These members constitute the wire cutting mechanism. Thus, when the tag 65 reaches the conveying belts 80 and 80^a and is gripped thereby, the movable member 65^b, 75

which projects slightly inwardly, contacts with the stationary trip 65^e secured upon the under side of the stationary disk or plate 64^b, such movable knife member 65^b swinging upon its pivot 65^c and cutting the wire at a point between the stationary knife member 65^a and the movable knife member 65^b. 80

In the meantime, the lower end of the wire, which, by the further feeding action suggested, has been projected through the tag 65 held by the fingers 60, moves down into free space, due to the departure of the pintle 52^c onward. At this juncture, however, plunger 70^e engages a cam 70^e upon the post 4, thereby forcing a tension member 70^a apertured as indicated at 73 in Figure 9 outwardly to receive the wire in its aperture and be subsequently forced inwardly by a spring 70^d to carry and hold the wire against a stationary tension member 70. 90

The lower end of the wire is so retained until the wiring mechanism revolves sufficiently to swing the outer end of the tag into the grip of a pair of superposed conveying belts 80 and 80^a, whereby the tag will be gradually drawn from the wiring mechanism together with its quota of wire. It will be seen that this quota or length starts at the high point, where severed by the action of the knife members 65^a and 65^b, and continues down through the wire-directing tube 58^b, the aperture in the tag, and the aperture in the tension member 70^a, terminating at some distance below the latter. Now, as the tag is drawn further in a lateral direction by the conveying belts, it pulls the wire length from a point intermediate its ends, forming a fold in the wire, so that one section is drawn from the wire directing tube 58^b above, and another section is drawn from the tension member 70^a below. 100

In this connection it will appear that, while that section of the wire leading to the tension member 70^a is exposed and subject to the tug of the tag, the upper section is still fully encased in the tube 58^b, or nearly so, being subjected to a right-angle fold or bend when drawn out. To obviate the difficulty of drawing the section from the tube as normally positioned, the cam 59 acts as the wire sections receive the tug of the departing tag, 110

to raise the tube a sufficient distance—through the agency of the parts 59^c, 59^d, etc.—to relieve the issuing wire section of the strain. However, as both wire sections or strands must be firm or taut enough to 120

105

115

120

125

130

135

140

meet certain twisting devices 90 to be described later, a small amount of resistance is imparted to them as against the pulling action of the tag. Thus, the lateral issue 5 of the upper strand from the tube 58^b will be somewhat deterred by the friction of the vertically movable section thereof within the tube; and the lower strand will be similarly affected as the tension member 70^a 10 presses it against the tension member 70.

As the tag 65 moves onwardly towards the delivery end of the machine, the revolving twisters 90 twist the two strands of wire adjacent the tag opening, the tag afterwards 15 drawing the wires from the twisting members 90 and being delivered at the delivery end of the machine by the belts 80 and 80^a.

The wire twisters 90 are mounted upon respective shafts 90^a revolvably mounted in 20 the brackets 90^b, the shafts 90^a having at their inner ends the grooved pulleys 90^c, the brackets 90^b being secured upon the power shaft 22 by the screw 90^d or other suitable securing means, the bracket 90^b being revolved 25 in the direction of the shaft 22 and being supported by the pintle 90^e mounted in the bracket support 90^f. While the bracket 90^b is being revolved in one direction by the shaft 22, the pulleys 90^c, shafts 90^a and 30 wire twisters 90 are rotated in the opposite direction by the belt 15 as hereinbefore described.

The conveying belt 80 rides upon a small pulley 81 mounted upon a vertical plate 100 35 supported upon one corner of the machine and also around a larger pulley 81^a also mounted upon the plate 100 slightly remote from the delivery end of the machine. The belt 80^a travels around the small pulley 82 40 and the driving pulley 82^a and around a second small pulley 82^b, the pulley 82 being mounted upon the plate 100 at the delivery end of the machine, whilst the pulley 82^b is mounted upon the plate 100 remote 45 from the delivery end of the machine. The pulley 82^a is rigidly secured upon the driven shaft 22 whereby the pulleys 82^a drives the belt 80^a in the direction of the arrows and through the frictional engagement 50 between the belts 80^a and 80, the belt 80 is likewise driven in the same direction as indicated by the arrows. These belts constitute the conveying belts for receiving the tags 65 from the wiring mechanisms and 55 discharging the completed tag to the delivery end of the machine.

As the wire twisters 90 are intended to impart but a limited number of turns to the wire, provision is made to check the rotation of the twisters after the requisite number of turns have been given, and to place them in receptive position for the next set of wires. Thus, the stationary pintle 90^e is fitted with a disk cam 91, which 60 is fixed, and inside the path of the revolv-

ing twister assembly, as the latter turns in a clockwise direction, per Figure 2. The cam 91 has a drop or fall opposite the side at which the tag wires are engaged by the twisters, and the twister pulleys 90^c have a 70 projecting lug 92 co-operating with the periphery of the cam. As the twisters are carried around the cam 91, they are, during the greater part of their course prevented from rotating on their own axes by the riding of the lugs 92 on the high portion of the cam periphery. However, when a given twister rises to wire-receiving height, its lug 92 arrives opposite the drop or low portion of the cam periphery, clearing the same and 80 permitting the twister to rotate a sufficient number of turns and impart a corresponding number of twists to the tag wires. The intermittent motion of the twisters will cause no appreciable amount of friction 85 with the belt 15, as but a small amount of slippage is required, i. e., with the twister approaching the wire receiving point. The twister at the other side may be permitted to rotate idly until it assumes the proper 90 receiving position of itself, as explained above.

Having thus described my invention, what I claim as new and desire to secure by Letters Patent is:

1. A machine of the character specified comprising a fixed cam having guiding means, a movable cam associated with the fixed cam and having guiding means, a tag engaging spindle engaging said guiding means, spring means urging said spindle to a predetermined position with respect to said first and second-named cams, and means to periodically arrest the movement of said spindle, said spindle being provided 100 with tag engaging means adapted to conduct the tags from a source of supply to a tag working mechanism.

2. A machine of the character described comprising a fixed cam having an internal 110 guide opening, a rotatable cam associated with the fixed cam and having a guide opening, a spindle extending through said openings, spring means urging said spindle to a predetermined position, and means to periodically arrest the movement of said spindle, said spindle being provided with tag engaging means whereby to conduct the tags from a source of supply to a tag wiring 115 mechanism.

3. A machine of the character described comprising a fixed cam having a guide opening, a rotatable cam having a guide opening in registration with the guide opening in said fixed cam, a spindle freely extending through said openings, means urging said spindle to a predetermined position in said openings, said spindle being provided with a tag engaging pintle located above said fixed cam and adapted to engage a tag at 130

the point of supply and convey the tag to the wiring mechanism.

4. A machine for wiring tags comprising a pair of fixed cams arranged in spaced relation and having guide openings, rotatable cams between said fixed cams and having pairs of openings in registration with the openings in said fixed cams, spindles extending freely through said openings in said first and second named cams, a spring urging said spindles to predetermined positions, and means to periodically arrest the movement of said spindles with said rotatable cams.

15 5. A machine for wiring tags comprising a pair of fixed cams arranged in spaced relation and having guide openings, rotatable cams between said fixed cams and having pairs of openings in registration with the 20 openings in said fixed cams, spindles extending freely through said openings in said first and second named cams, a spring urging said spindles to predetermined positions, and means to periodically arrest the 25 movement of said spindles with said rotatable cams, said spindles being provided with pintles for extending through the perforation in a tag and conveying the tag to a wiring mechanism.

30 6. In a tag wiring machine, the combination with a tag receiving means, of a wire applying means, means for ejecting the tags in succession from said tag receiving means, means co-operating with a conducting means 35 for placing the tags upon said wire applying means, means for receiving and retaining said tags upon said wire applying means while the wire is being applied to the tags, means for holding the fed wire under tension, means for severing the fed wire, and means for twisting the severed strands of 40 wire for securing the same upon the tags.

7. In a tag wiring machine, the combination with a tag receiving means, of a wire 45 applying means, means for conducting the tags from said tag receiving means to said wire applying means, means upon said wire receiving means for operatively retaining the tags thereon during the feeding of the wire, means for holding the fed wire under 50 tension, means for severing the wire held under tension, means for releasing the tension upon the wire, means for conveying the tags to the delivery end of the machine upon their release from said wire applying means, and means for twisting the wire upon the 55 tags during their transit towards the delivery end of the machine.

8. A machine for wiring tags comprising 60 a rotatable member having uprights, a carrier mounted on said uprights and having movable wire directing tubes, and wire feeding means mounted on said carrier and movable therewith.

65 9. A machine for wiring tags comprising

a rotatable member having uprights, a carrier mounted on said uprights and having movable wire directing tubes, and wire feeding means mounted on said carrier and movable therewith, levers connected to said wire directing tubes, and means for rocking said levers at intervals whereby said wire directing tubes are periodically operated.

10. A machine for wiring tags comprising a rotatable member having uprights, a carrier mounted on said uprights and having movable wire directing tubes, and wire feeding means mounted on said carrier and movable therewith, levers connected to said wire directing tubes, and tag engaging 75 fingers having means whereby the same are urged toward said wire directing tubes.

11. A machine for wiring tags comprising a rotatable member having uprights, a carrier mounted on said uprights and having movable wire directing tubes, and wire feeding means mounted on said carrier and movable therewith, levers connected to said wire directing tubes, and means to periodically move said tag engaging fingers away 80 from said wire directing tubes.

12. A machine for wiring tags comprising a rotatable member having uprights, a carrier mounted on said uprights and having movable wire directing tubes, and wire feeding means mounted on said carrier and movable therewith, levers connected to said wire directing tubes, and means to engage the wire upon passing through the tag whereby 85 to tension the wire.

13. A machine for wiring tags comprising a rotatable member having uprights, a carrier mounted on said uprights and having movable wire directing tubes, and wire feeding means mounted on said carrier and movable therewith, levers connected to said wire directing tubes, and conveying belts to engage the tag and convey the same to a point 90 of discharge.

14. A machine for wiring tags comprising a rotatable member having uprights, a carrier mounted on said uprights and having movable wire directing tubes, and wire feeding means mounted on said carrier and movable therewith, levers connected to said wire 105 directing tubes, and a twisting mechanism to engage the wire when the tag is being conveyed to a point of discharge.

15. In a tag wiring machine, the combination with a tag receiving means, of a wire applying means, means for conducting the tags from said tag receiving means to said wire applying means, means for directing the course of said tag conducting means, means upon said wire applying means for receiving the tags from said conducting means, means for successively feeding a section of wire to a plurality of tags during their traverse through said wire applying means, means for conveying the tags with their wire sec- 120 125 130

tions from the wire applying means to the discharge end of the machine, and means for twisting the sections of wire upon the tags during their transit with said conveyor.

- 5 16. In a tag wiring machine, the combination with a tag receiving means, of a wire applying means, means for conducting the tags from said tag receiving means to said wire applying means, means for directing 10 the course of said tag conducting means, means upon said wire applying means for receiving and retaining the tags from said conducting means, means for successively feeding a section of wire to a plurality of 15 tags during their traverse through said wire applying means, means for conveying the tags with their wire sections from the wire applying means to the discharge end of the machine, and means for twisting the sections 20 of wire upon the tags during their transit with said conveyor.

17. In a tag wiring machine, the combination with a tag receiving magazine, of a wire applying means, said means consisting of a revoluble unitary structure comprising wire directing means, wire feeding means, tag retaining means co-operating with said wire directing means, wire severing means, and

means for feeding the tags to said wire applying means.

18. In a tag wiring machine, the combination with a tag receiving magazine, of a wire applying means, said means consisting of a revoluble unitary structure comprising wire directing means, wire feeding means, tag retaining means co-operating with said wire directing means, wire severing means, and a revoluble wire twisting means for engaging the wire subsequently to the actuation of the wire severing means.

19. In a tag wiring machine, the combination with a tag receiving magazine, of a wire applying means, said means consisting of a revoluble unitary structure comprising wire directing means, wire feeding means, tag retaining means co-operating with said wire directing means, wire severing means, a revoluble wire twisting means for engaging the wire subsequently to the actuation of the wire severing means, and means for conveying the completed tag from said wire applying means and said wire twisting means to the discharge end of the machine.

In testimony whereof I affix my signature,

IRVIN L. YOUNG.
